CLAIM

The ornamental design for a lid for a container, as shown and described.

DESCRIPTION

FIG. 1 is an upper left perspective view of a lid for a container, illustrating the container in a closed position; FIG. 2 is an upper right perspective view of the lid for a container shown in FIG. 1;

FIG. 3 is a lower right perspective view of the lid for a container shown in FIG. 1;

FIG. 4 is a left side view of the lid for a container shown in FIG. 1;

FIG. 5 is a right side view of the lid for a container shown in FIG. 1;

FIG. 6 is a rear view of the lid for a container shown in FIG. 1;

FIG. 7 is a front view of the lid for a container shown in FIG. 1;

FIG. 8 is a top view of the lid for a container shown in FIG. 1;

FIG. 9 is a bottom view of the lid for a container shown in FIG. 1;

FIG. 10 is an upper left perspective view of a lid for a container, illustrating the container in an open position;

FIG. 11 is an upper right perspective view of the lid for a container shown in FIG. 10;

FIG. 12 is a lower right perspective view of the lid for a container shown in FIG. 10;

FIG. 13 is a left side view of the lid for a container shown in FIG. 10;

FIG. 14 is a right side view of the lid for a container shown in FIG. 10;

FIG. 15 is a rear view of the lid for a container shown in FIG. 10;

FIG. 16 is a front view of the lid for a container shown in FIG. 10;

FIG. 17 is a top view of the lid for a container shown in FIG. 10; and,

FIG. 18 is a bottom view of the lid for a container shown in FIG. 10.

(Continued)

The broken lines in the drawings illustrate portions of the lid for a container which form no part of the claimed design.
